UNITED STATES PATENT OFFICE

ARTHUR HOPPE, OF RIVER EDGE, NEW JERSEY, ASSIGNOR TO J. R. WOOD & SONS, INC.,
OF BROOKLYN, NEW YORK, A CORPORATION OF NEW YORK

DESIGN FOR A FINGER RING

Application filed January 25, 1933. Serial No. 46,979. Term of patent 14 years.

To all whom it may concern:

Be it known that I, ARTHUR HOPPE, a citizen of the United States, residing at River Edge, in the county of Bergen and State of New Jersey, have invented a new, original, and ornamental Design for a Finger Ring, of which the following is a specification, reference being had to the accompanying drawing, forming part thereof, in which the figure

of the drawing is a perspective view of a finger ring showing my new design.

The design consists of a plurality of oblique lines which divide the spaces in which the stones may be mounted.

I claim:

The ornamental design for a finger ring, as shown and described.

ARTHUR HOPPE.
